PRINTING CYLINDER WITH INK BELTS FOR MULTICOLOR SINGLE IMPRESSION PRINTING

Frank V. Szasz, Mission, Kans.
(5816 Cherokee Drive, Shawnee Mission, Kans. 66205)
Filed Feb. 1, 1966, Ser. No. 524,152
3 Claims. (Cl. 101—176)

ABSTRACT OF THE DISCLOSURE

A printing cylinder has a plurality of elongated flexible inking belts arranged generally radially thereabout, the belts being adapted to cooperate with respective ink fountain assemblies and having effective peripheral lengths equal to the effective circumference of the printing cylinder. Positive drive means engage the printing cylinder and the inking belts for driving the printing cylinder in continuously synchronized peripheral registry with the inking belts.

This invention relates to improved printing apparatus and methods and more particularly, to an apparatus and method for multicolor printing with a single printing member.

Printing in multiple colors has become a highly developed art which is normally accomplished with complex printing apparatus including a plurality of spaced apart printing members and sophisticated register devices for maintaining the proper relative position of the printed image as it travels between the printing members for application of different colored inks. To applicant's knowledge, the only suggested automatic printing apparatus which prints multiple colors with a single printing member has been limited to the application of a single color along any line of longitudinal motion of the printed material. In certain cases, a single transfer blanket has been used to carry a two-color image to a web, but this required two synchronized printing plates or printing members. Further, known multicolor printing methods and apparatus, particularly when printing in more than two colors, are expensive and, therefore, often unsuitable to extensive use in printing newspapers, low cost advertising material and the like.

The principal objects of the present invention are to provide an improved apparatus and method which permits printing multiple colors with a single printing member; to provide such an apparatus and method which is not limited to the application of a single color along a line of longitudinal motion; to provide such an apparatus and method which is relatively inexpensive to build and use and may be easily adapted to existing printing presses; to provide such an apparatus and method which is well suited to high speed continuous web printing, but is not limited thereto; to provide such an apparatus and method which may be used for simultaneously printing a large number of colors simultaneously, for example, five; and to provide such an apparatus and method which is well suited for its intended purpose.

Other objects and advantages of this invention will become apparent from the following description taken in connection with the accompanying drawings wherein are set forth by way of illustration and example certain embodiments of this invention.

FIG. 1 is a fragmentary schematic cross-sectional side elevation of a preferred form of apparatus embodying this invention for printing a multicolored impression on a moving web.

FIG. 2 is a fragmentary schematic cross-sectional perspective view of the apparatus illustrating additional details.

2

FIG. 3 is a fragmentary cross-sectional view through the apparatus on an enlarged scale showing a typical contact area between an inking blanket and the printing cylinder.

5 FIG. 4 is a fragmentary cross-sectional view through the apparatus on an enlarged scale illustrating the use of a removable inking blanket on a flexible transfer belt.

10 FIG. 5 is a perspective view illustrating a transparent composing sheet overlaid on a printed proof sheet for 15 treating areas on the transparent sheet corresponding to the desired positions of a selected color on the final printed image.

FIG. 6 is a view similar to FIG. 5 but illustrating a second transparent sheet being treated for a second color.

15 FIG. 7 is a perspective view illustrating the use of a treated transparent sheet in producing an inking blanket for applying one color ink to the printing cylinder.

Referring to the drawings in more detail:

20 The reference numerals 1 generally indicates a preferred form of apparatus embodying this invention for printing multiple colors on a moving web with a single printing member. The apparatus 1, in this example, comprises a mill or feed roll 2 adapted to feed a web of paper 3 continuously over suitable guide rollers 4, 5, and 25 6. The guide roller 6 releases the paper 3 between an impression cylinder 7 and a printing member or cylinder 8 for printing thereon and a guide roller 9 directs the paper to other apparatus (not shown) for subsequent operations.

30 The printing cylinder 8 is simultaneously inked in five colors during each revolution thereof by inking members 10, 11, 12, 13 and 14 respectively comprised of a flexible belt 15 of the type known as a "timing belt" having spaced apart teeth 16 on the interior surface thereof. The 35 teeth 16 of each belt 15 are engaged with respective pairs of sprocket rollers 17 and 18 by which the belt may be driven synchronously with cooperating equipment. The belts 15 are respectively pulled into an elongated shape by the respective sets of rollers 17 and 18 so that relatively little circumferential space is taken about the printing cylinder 8 by each belt. This permits a relatively large number of belts, in this case five, to be simultaneously positioned adjacent the printing cylinder 8 by generally radial positioning, as best illustrated in FIG. 1. An 40 ink fountain assembly is provided for each of the inking members 10 to 14 inclusive and designated respectively 19, 20, 21, 22 and 23. Each comprises an ink fountain 24 and suitable inking rollers 25, 26, 27 and 28 which are used in a known manner to transport and apply ink under 45 controlled conditions to a receiving surface.

The printing cylinder 8 is covered by a suitable printing plate 29 which, in this example, is of the relief type (FIG. 3), but, if, desired, may be of the lithographic or intaglio type. The flexible belts 15, in this example, are covered 50 with inking blankets respectively designated 30, 31, 32, 33 and 34. The inking blankets are removably secured to the respective belts 15 by suitable means, for example, adhesive and in predetermined positions thereon as indicated by suitable alignment members 35 which fit into 55 corresponding receivers 36 on the belts. The inking blankets have ink transfer areas 37 thereon which, in this example, are characterized as being in relief, that is, raised above the base surface 38 of the blanket; however, the 60 ink transfer areas 37 may be characterized by ink accepting lithographic or intaglio areas without departing from the scope of the invention.

The ink transfer areas 37 may be positioned anywhere on the respective inking blanket, the only limitation being that inking areas of one blanket do not overlap corresponding positions of ink transfer areas on other blankets. The respective blankets, in this example, have a peripheral length equal to the circumference of the printing cylinder

8 at the effective diameter of the printing plate 29 and are driven synchronously with the printing cylinder 8 so that each ink transfer area 37 on the respective inking blankets always contacts the printing plate 29 at a predetermined position during each printing cycle. In this example, the synchronous driving of the inking blankets with the printing cylinder 8 is accomplished by a suitable prime mover 39, gear reducer 40 and drive shaft 41. The drive shaft 41 simultaneously rotates gears 42 and 43 which are respectively meshed with gears 44 and 45. The gear 44, through a shaft 46, drives a gear 47 which is meshed with a gear 48 driving the inking member 10. Idler gears 49 mesh with the gear 48 and additional gears such as 50 for simultaneously driving the remaining inking members 11, 12, 13 and 14. The gear 45, through a shaft 51, drives the printing cylinder 8 which contacts and prints on the web 3.

As noted above, the ink transfer areas 37 do not overlap corresponding areas 37 on other blankets. The respective areas 37, however, may exceed the size of the corresponding printing area 52 on the printing plate 29 which it services, FIG. 3, so long as there is no application of multiple colors on a single spot. The ink fountain assembly 19 is conventionally driven by structure (not shown) forming part of the overall press apparatus and respectively operate to apply ink of the desired color only on the ink transfer areas 37 of the respective inking blankets.

In operation, each of the ink fountains 24 may be charged with a different color ink. The ink is applied by the ink fountain assemblies to the respective inking blankets on the ink transfer areas 37 thereof. The respective transfer areas 37 contact only a particular predetermined printing area 52 on the printing plate 29 whereupon the different color inks are respectively applied to particular predetermined areas on the printing plate 29 in a single printing cycle. The different color inks are then simultaneously printed on the web 3 to produce various printed areas 53 of respectively different colors.

The ink transfer areas 37 on the respective inking blankets are preferably formed in the following manner; however, other methods of forming the ink transfer areas may also be used without departing from the scope of this invention. A blank proof sheet 54 is made from the printing plate 39, for example, entirely in black ink, and a transparent member such as an acetate sheet 55 is overlaid thereon. The composer may then take a suitable marking device such as a brush 56 and apply a suitable chemical to the sheet 55 on areas 56' corresponding to areas on the sheet 54 which he desires to be a particular color, FIG. 5. A second acetate sheet 57 is then applied over the proof sheet 54 and the composer treats the areas 57' which he desired to be printed in a second color, FIG. 6. This is repeated until a transparent sheet is completed for each color which the composer desires to use. The sheets may then be overlaid on respective sensitized blanket members 58 and the inking areas, for example 57', transferred thereto in a conventional manner, as by a suitable transfer light 60, FIG. 7. The respective blanket members 58 are then suitably treated, for example, by an etching process leaving the desired ink transfer areas thereon in relief. In the alternative, one of the well known "flexographic" methods for producing the ink transfer areas might be used. It is to be understood that, if desired, a single transparent sheet may be used and several

selective chemicals applied to the single sheet to determine the particular ink transfer areas for the respective blanket members 58, and suitable filters used to distinguish the colors in exposing the respective blanket members from the single sheet.

It is to be understood that while certain forms of this invention have been illustrated and described, it is not to be limited thereto except insofar as such limitations are included in the following claims.

What I claim and desire to secure by Letters Patent is:

- Apparatus for printing multiple colors with a single impression comprising:
  - a printing cylinder,
  - a printing plate removably mounted on said cylinder, said printing plate having a plurality of printing areas thereon respectively spaced from each other,
  - a set of first rollers circumferentially spaced-apart about and adjacent to said cylinder and having diameters substantially smaller than said cylinder, a set of second rollers generally radially spaced from said cylinder and aligned with said respective first rollers,
  - a plurality of ink fountain assemblies respectively adjacent said second rollers and each adapted to dispense a different color ink,
  - a plurality of elongated flexible inking belts respectively mounted on said aligned first and second rollers and each adapted to cooperate with one of said ink fountain assemblies for receiving ink therefrom, said inking belts having an effective peripheral length equal to the effective circumference of said printing cylinder,
  - positive drive means engaging said printing cylinder and said inking belts for driving said printing cylinder in continuously synchronized peripheral registry with said inking belts,
  - said inking belts each having an ink transfer area thereon corresponding to one of said printing areas and not overlapping a printing area serviced by another of said inking belts,
  - whereby during a single revolution of said printing cylinder, said printing plate receives thereon a plurality of different color inks respectively restricted to predetermined printing areas.
- The apparatus as set forth in claim 1 wherein:
  - said belts include drive teeth engaging said drive means.
- The apparatus as set forth in claim 1 wherein:
  - said ink transfer areas are positioned on blankets removably secured to said belts.
